UNITED STATES PATENT OFFICE.

WILBUR L. FULTON, OF OMAHA, NEBRASKA.

DRAWING-BOARD.

1,230,398.

Specification of Letters Patent. Patented June 19, 1917.

Application filed January 22, 1916. Serial No. 73,636.

To all whom it may concern:

Be it known that I, WILBUR L. FULTON, a citizen of the United States, residing at Omaha, in the county of Douglas and State 5 of Nebraska, have invented a certain new and useful Improvement in Drawing Boards, of which the following is a specification.

This invention relates to drawing boards 10 and provides a device of this class which may be taken apart and made into a compact package for shipment, whereby the bulk is reduced and risk of damage to the board is lessened.

15 It is essential that the drawing board when set up shall present a true plane surface free from cracks, and further that it shall provide at least one true straight edge to guide a T square.

20 To accomplish this purpose I construct a board of a plurality of sections each provided with suitable means for engaging two metallic cross bars of special form. Each of the cross bars is provided at one or both 25 ends with a clamping means for urging the several sections into close edge contact. One of the metal cross bars carries a straight edge for guiding the T square. To protect the edges of the board sections when separated, I provide a number of protector clips 30 which may be applied so as to incase the edges and prevent injury thereto.

The preferred embodiment of the invention is shown in the accompanying drawings, 35 wherein—

Figure 1 is a perspective view of the lower side of a drawing board constructed in accordance with my invention; .

Fig. 2 is a section through the board 40 showing the mode of mounting the cross bars;

Fig. 3 is a fragmentary view looking at the end of one cross bar and showing its clamping plate released;

45 Fig. 4 is a section on the line 4—4 of Fig. 3;

Fig. 5 is a view looking at the end of the other cross bar, but showing the clamping plate in holding position;

50 Fig. 6 is a perspective view of two adjacent board sections slightly separated and showing the holding batten carried on the under side of these;

Fig. 7 is a fragmentary sectional view 55 transverse to one of the cross bars, showing the straight edge carried thereby;

Fig. 8 is a perspective view of this cross bar and its attaching straight edge;

Fig. 9 is a fragmentary perspective view showing a protecting clip mounted on the 60 edge of one of the board sections; and

Fig. 10 is a section through a modified form of the device.

The board illustrated is composed of three sections 11. Each section is formed on 65 its rear face with transverse grooves 12 and 13, the grooves 13 being located at or very near one end of each of the respective sections. Each of the grooves 12 and 13 is provided with a batten 14 T-shaped in cross 70 section, the battens 14 being preferably of metal. They thus serve both as a means of attaching the cross bars hereinafter described and also as a means for preventing warping of the board sections. The cross 75 bars are preferably composed of two chords 15 and 16, tied together by bridging pieces 17, this form being adapted to secure strength with lightness. The chords 15 of the cross bars are provided with pairs of 80 opposed overhanging lugs 18, so formed as closely to embrace the heads of the T-shaped battens 14. The lugs 18 are preferably so spaced as to grasp the battens 14 adjacent each edge of each board section, 85 thus securing accurate alinement of the top surfaces of adjacent sections.

One cross bar, *i. e.* that which grasps the battens in the notch 13 near the edge of the board, carries a metal or other straight-edge 90 19 which extends upward and along the edge of the board to guide the T square as already suggested.

Each of the cross bars is provided at one or both of its ends with an adjustable tensioning means for pressing the board sections into close contact with each other. A tension screw 20 threaded into the end of the cross bar passes through a slot 21 of a resilient metal plate 22. This plate bears 95 against the shoulder on a thrust screw 23 and also against the end of a batten 14. Any desired stress may be placed upon the board sections by proper adjustment of the screws 20 and 23 as will be apparent from 100 an examination of Fig. 2. When it is desired to separate the board sections, one set of screws 20, 23 on each cross bar is loosened, the screw 23 being turned to clear plate 22, so that this may be slipped downward upon 105 the screw 20 to permit the withdrawal of the board sections from engagement with 110

the cross bars. When only one tensioning device is provided on each cross bar, a fixed stop lug is used in place of the plate 22 which is in effect an adjustable stop.

- 5 After the board sections have been separated in this way, their edges are protected by means of resilient U-shaped metal clips 24 which are slipped over them. See Fig. 9. Thus protected the board sections and the 10 cross bars may be safely transported and when needed for use are freed of the protecting clips, brought into engagement with the cross bars and then locked together by the use of the resilient clamping plates. 15 The metal parts may be nicely machined thus insuring an accurate fit of all the parts, and as the battens will prevent warping of the board sections, a true surface is assured. The particular form of the parts is subject 20 to variation, for example, the cross bars and battens may be designed to engage in a number of ways.

In Fig. 10 I illustrate a modification in which the engaging parts are reversed, the 25 T head being put on the cross bar and the engaging lugs on the board sections. In this case two battens 25 are mounted in each of the grooves on the upper sections, the battens 25 being provided with lateral 30 grooves to receive the flanged head 26 of cross bars indicated generally by the numeral 27.

Having thus described my invention, what I claim is:—

35 1. In a drawing board, the combination of a plurality of separable sections capable of being assembled edge to edge to present a suitable drawing-supporting surface; cross bars extending transversely to said sections; 40 interengaging members carried by said cross bars and each of said sections for releasably connecting said sections to said cross bars; and means for forcing said sections edgewise into contact and holding the 45 same in engagement with said cross bars.

2. In a drawing board the combination of a plurality of separable sections capable of being assembled edge to edge to present a suitable drawing-supporting surface;

transverse battens on each of said sections; 50 cross bars adapted to slide longitudinally into locking relation with the battens of a plurality of assembled sections; and clamping means for forcing said sections into close edge contact and for holding the same 55 in engagement with said cross bars.

3. In a drawing board, the combination of a plurality of sections capable of being assembled edge to edge to present a suitable 60 drawing-supporting surface; transverse battens having overhanging flanges mounted on the backs of each of said sections; cross bars having projecting portions adapted to slide longitudinally into engaging relation with the overhanging flanges of the battens 65 on a plurality of assembled sections; and clamps carried by said cross bars for forcing said sections into close edge contact.

4. In a drawing board, the combination of a plurality of sections capable of being 70 assembled edge to edge to present a suitable drawing-supporting surface; cross bars extending transversely to said sections; a straight edge carried by one of said cross bars, and extending along the ends of the 75 sections when assembled; and releasable interlocking means between said sections and cross bars for holding said sections in assembled relation.

5. In a drawing board, the combination 80 of a plurality of sections capable of being assembled edge to edge to present a suitable drawing-supporting surface; transverse battens having overhanging flanges mounted on the backs of each of said sections; cross 85 bars having projecting portions adapted to slide longitudinally into engaging relation with the overhanging flanges of the battens on a plurality of assembled sections; a straight edge carried by one of said cross 90 bars and extending along the ends of said sections; and clamps carried by said cross bars for forcing said sections into close edge contact.

In testimony whereof I have signed my 95 name to this specification.

WILBUR L. FULTON.
